UNITED STATES PATENT OFFICE.

HENRY C. MAUL, OF DETROIT, MICHIGAN, ASSIGNOR TO THE MICHIGAN STOVE COMPANY, OF DETROIT, MICHIGAN, A CORPORATION OF MICHIGAN.

PIPING FOR GAS-RANGES.

1,088,789.

Specification of Letters Patent.

Patented Mar. 3, 1914.

Application filed March 15, 1912. Serial No. 683,939.

To all whom it may concern:

Be it known that I, HENRY C. MAUL, a citizen of the United States, residing at Detroit, in the county of Wayne, State of Michigan, have invented certain new and useful Improvements in Piping for Gas-Ranges; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to a system of piping for gas ranges, and consists in the construction and arrangement of parts herein-after more fully set forth and pointed out particularly in the claims.

20 The object of the invention is to provide a simple arrangement for so disposing the main gas supply pipe as to enable the independent connection thereto of the burners for heating the cooking top, and the 25 burners for heating the oven of a gas range, provision being made for controlling a plurality of burners from one gas cock and for readily connecting a plurality of cooking ranges in a battery, and facilitating the 30 supplying of gas to the several burners of each range without interfering with the supply to the other ranges.

The above object is attained by the arrangement illustrated in the accompanying 35 drawing, in which:—

Figure 1 is an elevation of two gas ranges piped in accordance with my invention, and connected to show the manner of joining a plurality of ranges. Fig. 2 is a sectional view through the hollow couplings which connect the sections of the main gas pipe and through which gas is supplied to the burners of the range.

Referring to the characters of reference, 45 1 designates a gas range of any suitable type having a cooking top 2. Crossing the front of the range transversely, preferably near the top, is the main gas supply pipe 3 which may be made to supply gas to any number 50 of ranges desired. Each range is provided with side pipes 4 and 5 respectively, which extend vertically on each side of the oven door 6. The side pipe 4 at its upper end is provided with a horizontally extending portion 7 which crosses a part of the front of

the range, and which supplies gas to a plurality of burners 8 extending under the cooking top. The lower end of the side pipe 4 is provided with a horizontally extending portion 9 which crosses a part of the front 84 of the range at the bottom thereof to supply gas to a plurality of oven burners 10. The side pipes 4 and 5 are connected with the main supply pipe 3 through vertical couplings 11 in the form of hollow castings. 85 Each of the couplings 11 is provided at its upper end with a head 12 into one side of which the pipe 3 connects. At the opposite side of said head it is provided with laterally extending flanges 13. Two of these 70 heads are connected together by transverse bolts 14 passing through said flanges to effect a continuity of the supply pipe 3 through said heads, as clearly shown in Fig. 1, packing 15 being employed between the 75 faces of said heads to effect a tight joint. By employing the fittings or couplings 11 having the heads 12 provision is made for connecting a battery of ranges together as shown, and at the same time affording each 80 range an independent connection with the supply pipe. At the terminal of the supply pipe, as at the left of Fig. 1, the opening through the head 12 of the fitting 11 is closed by a plate 16 secured to the flange 85 13 of said head by bolts 17, the joint between the plate and head being rendered tight by the interposed packing 18. The lower ends of the fittings 11 are connected to the side 90 pipes 4 and 5 respectively through the medium of T-couplings 19. In each of the side pipes 4, below the point of connection of the fittings 11 therewith, is a gas cock 20 which controls the supply of gas to all of the oven burners 10. Also located in each 95 of the side pipes 4 and 5, above the point of connection of the fittings 11 therewith, is a gas cock 21 which controls the supply of gas to one-half of the burners under the cooking top.

Extending from the lower end of each of the side pipes 5 is a horizontal section 22 which supplies gas to a pilot burner or lighter 23 for the oven burners. In each of the side pipes 5 is a cock 27 which controls 105 the supply of gas to the lighter 23 of common and well known construction for the oven burners. Extending laterally from the upper end of each of the side pipes 5 is a pipe section 24 which supplies gas to the 110

remainder of the burners 8 under the cooking top. Communicating centrally with each of the sections of the supply pipe 3 on each range is a gas cock 25 which controls 5 the supply of gas to a pilot burner or lighter 26 for the burners under the top of the range.

It will be noted on referring to the left 10 of Fig. 1, at the bottom, that the ends of the pipes 9 and 22 are closed by caps 28. To connect said closed pipe ends and prevent the end of pipe 9 being bent downwardly by any weight placed thereon the 15 embracing sleeve 29 is employed, as shown at the right of Fig. 1.

The elbows at the lower ends of the side 20 pipes 4 and 5 are embraced by brackets 30, mounted on the bases of the ranges, which firmly hold said pipes in place. The hinge straps 31 of the oven doors 6 are provided with eyes which are mounted to turn upon the lower pipe sections 9 and 22.

It will be noted that the horizontal sections 7 and 24 extending inwardly from the 25 upper ends of the side pipes 4 and 5 respectively, each supplies gas to one-half of the burners under the cooking top. By this arrangement one-half of said burners may be controlled by either of the gas cocks 21, 30 enabling either side of the top to be heated, or both sides, as may be desired. It will further be noted that the oven burners may be controlled entirely independently of the burners under the cooking top; that all of 35 the oven burners may be supplied with gas by opening the gas cock 20, and the supply of gas to said burners cut off by closing said cock.

The arrangement herein shown provides 40 for simultaneously supplying gas to all of the oven burners and to all of the burners

under the cooking top without interference. Attention is called to the fact that by reason of the arrangement shown the connection of a battery of gas ranges to a source of gas 45 supply is greatly facilitated, and that other ranges may be readily added to the battery from time to time as desired.

By connecting the sections of the supply pipe together by the fittings as shown, a battery of gas ranges may be supplied with gas in such a manner as to enable any one of the units to be removed without disturbing the other units of said battery.

Having thus fully set forth my invention, what I claim as new and desire to secure by Letters Patent, is:—

1. A gas range having a series of burners under its cooking top and a series of burners under the bottom of its oven, a horizontal main feed pipe, an auxiliary top feed pipe supplying the top burners, an auxiliary bottom feed pipe supplying the oven burners, a vertical supply pipe connecting said auxiliary pipes, and a fitting connecting the main supply pipe with the vertical supply pipe at a point between said auxiliary pipes.

2. In a gas range, a horizontal feed pipe co-extensive with said range, a fitting at 70 each end of said pipe for effecting a closure thereof or connection with the succeeding pipe section, burners for said range, auxiliary feed pipes communicating with said burners and connected with each of 75 said fittings respectively.

In testimony whereof, I sign this specification in the presence of two witnesses.

HENRY C. MAUL.
